UNITED STATES PATENT OFFICE.

KARL AUGUST EKBERG, OF NEW YORK, N. Y., ASSIGNOR OF ONE-HALF TO E. NORD-LUND, OF BROOKLYN, NEW YORK.

CIRCUIT-CLOSING DEVICE.

Application filed July 30, 1925. Serial No. 46,984.

This invention relates to switches for closing electric circuits, such switches being particularly designed for the actuation of burglar and hold-up alarms.

5 One important object of the present invention is to provide an improved general construction of switch for this purpose adapted to be actuated either manually or by the foot.

10 A second important object of the invention is to provide means for latching the switch in closed position and holding it against accidental opening.

Figure 1 is a perspective view of the improved switch.

Figure 2 is a perspective view of a controlling device used in connection with said switch.

Figure 3 is an end view of the switch as shown in Figure 1.

In carrying out my invention 10 designates a baseboard of insulating material upon which are fastened the lugs 11 of substantially springy S-shaped clips 12 having forti- 25 wardly curving lips 13 in which are held the ends of a tube or tread 14, suitable stems 15 being designed to prevent the frontwise displacement of the tube 14 when the stems 15 stand upright as shown in Figures 1 and 3, 30 these stems having integral rods 16 serving as pintles, encased in brackets 17, for the purpose of allowing stems 15 to be turned down to allow the displacement of the tube when tread upon by a persons foot.

35 In the tube 14 is an electrical cable or conduit 18 holding twisted together the wires that lead to the coils to be hereinafter described. The circuit maker and breaker proper consists of the handle 23 secured to 40 a lug 24 forming part of a knife switch 25 carrying the contact element 27 secured by a fastener 26 to blade or switch 25. A coil spring 28 supports the lug 24 underneath, the blade 25 being fulcrumed on the pin 29 secured in a bracket 30 connected to the baseboard 10. The spring 28 surrounds a stud 29 on the baseboard 10. A fixed contact 31 is carried by the member 32 secured to baseboard 10, this contact 31 being en- 45 gageable by the contact element 27 of the switch blade 25. A device is mounted on the baseboard 10 which is designed to separate the switch 25 from contact 31 independ- 50 ently of the tube 14. This device consists 55 of an arm 36 formed integrally upon a

knuckle 34 trunnioned upon the cross rod of a staple 33 secured into the baseboard 10. A lug 35 is also integrally formed upon the knuckle 34 and is disposed at right angles to the arm 36. In the position of this device shown in Figure 4 the lug 35 is up, holding up the switch blade 25 in a manner to separate the contact element 27 from the contact 36 thus opening the circuit. In this position it will be seen that the handle or arm 36 lies 60 down on the face of the baseboard 10. When the arm is raised the knuckle turns and this brings the lug 36 down to horizontal position, in which position the switch is set for controlled operation thru the displaceable 70 tube 14.

If a burglar or bandit enters any room wherein is installed the device shown in Figure 4 or its equivalent, it will be observed that the device will be within easy reach of 75 the foot of the person approached by the burglar. When the burglar commands the attendant to throw up his or her hands this is down but the foot of the person intimidated depresses the tube 14, displacing the 80 same as shown in Figure 12, whereupon the tube 14 no longer presses down upon the handle 23 of the switch against the tension of depressed spring 28; now when the tube 14 is thus displaced the spring 28 relapses 85 and throws up the handle 23 of the switch at its outer end causing the inner end of switch 25 to lower and engage the contact 36 thus closing the circuit. The bandit may now be in the act of committing a depredation within the room, without any knowledge of what is set into action by the displacement of the tube 14, which he may not see. 90

An electrical circuit is maintained in the 95 usual way so that upon the closing of switch controlled circuit an alarm may be conveyed.

There has thus been provided a simple and efficient device of the kind described and for the purpose specified.

100 It is obvious that minor changes may be made in the form and construction of the invention without departing from the material spirit thereof. It is not, therefore, desired to confine the invention to the exact form herein shown and described, but it is desired to include all such as properly come within the scope claimed.

105 What I claim and seek protection on is:—
110 1. A circuit controlling device comprising

a normally open switch, a spring urging the switch to closed position, a handle projecting from the switch, a pedal operated bar normally engaging the switch to hold the same open, and displaceable latch means movable independently of and engaging the bar for holding the bar against movement to release the handle.

2. A circuit controlling device comprising

10 a normally open switch, a spring urging the switch to closed position, a handle projecting from the switch, a pedal operated bar normally engaging the switch to hold the same open, displaceable latch means movable independently of and engaging the bar for holding the bar against movement to release the handle, and a releasable locking element engaging said switch to prevent closing thereof upon displacement of said bar.

15 20 3. A circuit controlling device comprising a normally open switch, a spring urging the switch to closed position, a handle projecting from the switch, a base supporting said switch, a pair of spaced hook members fixed 25 to the base on opposite sides of the switch, and a bar removably engaging said hook to restrain the switch from closing under the influence of said spring.

4. A circuit controlling device comprising 30 a normally open switch, a spring urging the switch to closed position, a handle projecting from the switch, a base supporting said switch, a pair of spaced hook members fixed

to the base on opposite sides of the switch, a 35 bar removably engaging said hook to restrain the switch from closing under the influence of said spring, and a pair of latches pivotally mounted on said base adjacent said hook members to swing along side of and away from said bar on the side of the bar 40 toward which it is moved for release from the hook members.

5. A circuit controlling device comprising a normally open switch, a spring urging the switch to closed position, a handle projecting from the switch, a base supporting said switch, a pair of spaced hook members fixed to the base on opposite sides of the switch, a bar removably engaging said hook to restrain the switch from closing under the influence of said spring, a pair of latches pivotally mounted on said base adjacent said hook members to swing along side of and away from said bar on the side of the bar 45 toward which it is moved for release from the hook members, and a latch member pivoted to the base below the switch and having an arm engageable with the switch upon the latch member being turned to one position whereby closing of the switch is prevented 50 independently of the removal of the bar.

In witness whereof he has hereunto set his hand and affixed his seal this sixth day of July, 1925.

KARL AUGUST EKBERG. [L.S.]
